UNITED STATES PATENT OFFICE

FRIEDRICH LERNER, OF VIENNA, AUSTRIA

MACHINE FOR THE MANUFACTURING OF MOUTHPIECE PLUGS AND FOR THEIR
INSERTION IN CIGARETTE TUBES

Application filed July 2, 1931, Serial No. 548,423, and in Austria April 11, 1931.

This invention relates to a machine adapted to work in accordance with this method by means of which the mouth-piece plugs are manufactured and inserted into the cigarette tubes.

It is usual to manufacture the plugs referred to of filtering absorbent material, such as crepe paper, cellulose, cotton-wool, or the like, in such a manner that a strip 10 composed of several layers of the material employed is taken from a roll and passed through shears up to a rolling device in which the severed piece of the strip is rolled or twisted into a round plug. The rolled 16 plug is then thrust by a rammer from the rolling device into a tubular member, the so-called spoon, over the end of which the cigarette tube is fitted.

This mode of operation has the disadvantage that in the process of twisting the plug 20 in the hollow space within the rolling device, which consists of a set of rollers, the plug becomes only approximately round, and is moreover distended in the intermediate 25 spaces between the annularly disposed twisting rollers, in consequence of the toughness of the fine fibres of the material employed. The consequence of the described weaknesses 30 of the commonly practised method of manufacture is that on the ejection of the plug into the spoon the diameters of the plug and of the spoon are not in conformity, with the result that the machine is often disturbed or interrupted in its working.

35 In accordance with this present invention this drawback is obviated by providing that the plug be formed by applying pressure to the ends of a flat lying strip of material.

40 In carrying this invention into effect I provide a pair of press cheeks forming together a hollow chamber and adapted to be opened to a distance at least equal to the length of said strip, so that this strip may 45 be inserted between the opened cheeks with its edge parallel to the direction of their closing movement and formed between them to a plug of the cross section of said hollow chamber.

50 The machine working according to this

method and with said pressing device exhibits the following novel features:—

Since the roll of material from which the mouth-piece plugs are formed consists of a loose fibrous material partly impregnated 55 with chemical matter, the roll is generally irregularly shaped and fragile. In order to enable the material to be unwound without disturbance, the roll of material is mounted in accordance with the invention upon a horizontal or approximately horizontal plate-like carrier, the material being continuously and uniformly unwound and conducted through shears which sever pieces of the required length.

55 For this purpose a conveyor wheel is provided immediately in front of the shears which rotates with uniform and regulatable speed, whereby a uniform feed of the strip of material is obtained.

60 The axle of the conveyor wheel is adapted to be rocked about an axis parallel to the direction of the feed movement of the strip of material, in order to enable the conveying 65 to be easily adjusted.

65 The piece of the strip severed by the shears is thrust by means of a reciprocating slide into the press, whereupon the movable press-cheek thrusts the strip against the fixed cheek of the press, thereby forming the 70 plug. According to the invention the press-cheeks are oval shaped so that the pressed plug is of elliptical section.

75 The oval shape of the press cheeks causes the plug after pressing to become of round 80 section in consequence of the higher tension in the horizontal direction.

85 The plug thus formed is thrust by a rammer into a sleeve—the so-called spoon—provided in front thereof, over which sleeve the cigarette tube is fitted. The spoon, 90 which is secured in a known manner within a turnable disc is then advanced one step about the axis of the disc and the next 95 spoon is brought into position in front of the opening of the press, while the spoon provided with a plug and a tube is brought in front of a second rammer. The latter removes the plug and the tube simultane- 100

ously from the spoon into a collecting container.

The rammer for removing the plugged tube from the spoon is connected with a stripper adapted to slide upon the outside of the spoon and to strip off the tube, while the said rammer pushes the plug forward within the interior of the spoon. This arrangement enables unslotted spoons to be employed and ensures that the ends of the tube and of the plug register.

The machine according to the invention is illustrated diagrammatically in a constructional example, in the accompanying drawings, in which:—

Fig. 1 is a front view and

Fig. 2 is a plan view of the machine,

Fig. 3 illustrates the arrangement of the conveyor wheel

Fig. 4 shows the rammers for the moving forward of the plug,

Figs. 5 and 6 demonstrate the press for forming the plug, in two operative positions,

Fig. 7 shows the closed press form and the spoon on an enlarged scale,

Fig. 8 shows the rammer and the stripper for removing the plug and the tube from the spoon, and

Fig. 9 is a section taken on the line IX—IX of Fig. 8.

On the machine bed 1 (Figs. 1 and 2) there is attached a bearing 2 which carries

on its end a bolt 3 about which the bobbin-carrier 4 is horizontally and rotatably mounted. The bobbin-carrier 4 has a central pin 5 which receives the roll of material 6 for the mouth-piece fillers and by means of springs provided locks the roll against rotation.

The strip of material 6 is conducted through a channel 7 with an adjustable side wall 8 in which the conveyor wheel 9 is pressed against the strip of material 6. At the other end of the shaft 10 of the conveyor wheel 9 there is attached a stepped grooved disc 11. A counter-disc 12 is attached to a shaft 13 which carries a toothed wheel 14. The latter engages in the toothed wheel 15 on the main shaft 16 of the machine and is driven uniformly and continuously. A cord 17 transmits the rotary movement of the shaft 13 and of the pulley disc 12 to the pulley disc 11 and the conveyor wheel 9.

The shaft 10 of this latter runs in a bearing 18 which is tiltable about a pin 19. In the bearing 18 there is rotatably mounted a bolt 20 traversed by a set-screw 21 which projects as far as a fixed stop. By means of this screw 21 the pressure of the conveyor wheel against the strip of material 6 can be accurately adjusted. On the tilting of the screw 21 about the axis of the bolt 20 the conveyor wheel 9 can

be lifted out of the guiding channel 7.

The shaft 13 of the pulley disc 12 is mounted in a holder 48 which is tiltable about the shaft 16, and which is under the action of a spring 22 and maintains a uniform tension of the cord 17.

The strip of material 6 is passed by the conveyor wheel through a fixed shearing device continuously on to a table 24 (Figs. 1 and 2).

The piece of the strip 6 severed by the shears is thrust, evenly spread as it lies upon the table 24, into the open pressing device by means of a reciprocating slide 25. The pressing device consists of a fixed part 26 and a movable part 27 adapted to perform a straight line reciprocating movement, thereby opening and closing the press-form. A cover plate 28 limits the space within the open press-form from above.

The specially shaped working ends 29, 30 (Figs. 5 and 6) of the press-cheeks are made interchangeable, so as to enable plugs of whatever cross-section and size to be manufactured.

The curvature of the working surfaces of the press-cheeks 29, 30 (Figs. 5 and 6) is so designed, that, as shown in Fig. 7, the transverse axis of the hollow chamber measured in the direction of the movement of the press-cheeks is smaller than the transverse axis of the spoon 36. After the ejection of the plug from the pre into the spoon, the plug expands and accommodates its cross-sectional dimensions to those of the interior of the spoon.

The plug thus shaped is thrust by the rammer 37 from the press into the spoon 36, the center line of which registers with that of the hollow chamber of the press. The spoons 36 are mounted in an intermittently revolved disc 35. A length of cigarette tubing is arranged in the protracted axis of the closed hollow form of the press and of the spoon. The tube severed from the length is fitted upon the spoon. A wheel 38 rotating in the direction of the arrow indicated in Fig. 4 causes the tube to hasten forward in advance of the lagging length of tubing, when being fitted upon the spoon.

After the moving forward one step of the disc 35 with the spoons 36, the spoon provided with plug and tube is brought into a position so as to register with the rammer 40. The rammers 37 and 40 are interconnected and are simultaneously operated by a driver 41 (Fig. 4). With the rammer 40 there is connected a tongue 31 (Figs. 4 and 8) which during the forward stroke of the rammer 40 (towards the right in Figs. 4 and 8) slides upon the spoon 36, thereby causing the tube to be stripped from the spoon, whilst the rammer ejects the plug from the spoon. In order to enable the tongue 31 to pass through the spoon disc 35, openings 32 (Figs. 8 and 9) are provided

in the latter. By the provision of various means for removing the plug and the tube from the spoon, slots and openings in the tubular wall of the spoon can be dispensed with, and spoons with an uninterrupted wall can be employed, thus the pressed plug is prevented from enlarging or deforming the spoon by its tension.

The reciprocating movement of the driver 41 and of the parallel guided rammers 37 and 40 is derived from a rocking lever 42 (Fig. 4). The latter is operated by a cam-disc 43 on the rotating machine shaft 44. The spring 33 causes the roller 46 of the lever 42 to be constantly pressed against the periphery of the cam-disc 43.

It will be noted that the invention is not intended to be limited to the embodiment herein described by way of example, but that it may equally well be applied to other similar and equivalent structures for the manufacturing of mouth-piece plugs with the employment of pressing devices.

I claim:—

1. In a machine for manufacturing mouth-piece plugs for cigarettes and cigarette tubes, a pressing device having a pair of press cheeks capable of relative movement, one with respect to the other, from a position spaced apart from one another to enable a length of evenly spread plug-forming material to be placed between them to a position approached to one another, said press cheeks having concave working surfaces so as to form together a hollow chamber when the press cheeks are approached to one another for shaping the plug-forming material into a plug, a feed device for feeding lengths of plug-forming material between said cheeks in the spaced apart position of the latter and means for removing the formed plugs from the said hollow chamber.

2. In a machine for manufacturing mouth-piece plugs for cigarettes and cigarette tubes, a pressing device comprising a pair of press cheeks and fixed guiding means for said cheeks enclosing the cheeks on three sides only, one of said cheeks being fixed and the other adapted to reciprocate in relation thereto from a position with the cheeks spaced apart from one another to enable a length of evenly spread plug-forming material to be placed between them to a position approached to another, said cheeks having concave working surfaces so as to form together a hollow chamber when the press cheeks are approached to one another, a feeding device for feeding lengths of evenly

spread plug-forming material between the cheeks arranged to thrust the said lengths through the open fourth side of the said fixed guiding means, the stroke of the reciprocatable cheek being at least equal to the length of the evenly spread plug-form-

ing material, and means for removing the formed plugs from said hollow chamber.

3. In a machine for manufacturing mouth-piece plugs for cigarettes and cigarette tubes, a horizontal holder for supporting a rolled strip of plug-forming material, conveying means for unwinding said strip of plug-forming material, a shearing device arranged to receive the material unwound by the said conveying means for dividing said material into separate lengths, a pressing device having a pair of press cheeks capable of relative movement, one with respect to the other, from a position spaced apart from one another to enable a length of evenly spread plug-forming material to be placed between them to a position approached to one another, said press cheeks having concave working surfaces so as to form together a hollow chamber when the press cheeks are approached to one another for shaping the plug-forming material into a plug, a feeding device for feeding lengths of plug-forming material between said cheeks in the spaced apart position of the latter and means for removing the formed plugs from the said hollow chamber.

4. In a machine for manufacturing mouth-piece plugs for cigarettes and cigarette tubes, a horizontal holder for supporting a rolled strip of plug-forming material, a rotary conveyor wheel arranged to unwind said strip of plug-forming material, a supporting shaft for said conveyor wheel, supporting means for said shaft pivoted so as to be capable of tilting the shaft about an axis parallel to the direction of travel of the strip of material, adjusting means for setting the shaft supporting means, a shearing device arranged to receive the material unwound by the said conveyor wheel for dividing said material into separate lengths, a pressing device having a pair of press cheeks capable of relative movement, one with respect to the other, from a position spaced apart from one another to enable a length of evenly spread plug-forming material to be placed between them to a position approached to one another, said press cheeks having concave working surfaces so as to form together a hollow chamber when the press cheeks are approached to one another for shaping the plug-forming material into a plug, a feeding device for feeding lengths of plug-forming material between said cheeks in the spaced apart position of the latter and means for removing the formed plugs from the said hollow chamber.

5. In a machine for manufacturing mouth-piece plugs for cigarettes and cigarette tubes, a horizontal holder for supporting a rolled strip of plug-forming material, a rotary conveyor wheel arranged to unwind said strip of plug-forming material, a sup-

- porting shaft for said conveyor wheel, a bearing for said shaft pivoted so as to be capable of tilting with the shaft about an axis parallel to the direction of travel of 5 the strip of material, a set screw operatively connected to said bearing for setting the bearing, a shearing device arranged to receive the material unwound by the said conveyor wheel for dividing said material into 10 separate lengths, a pressing device having a pair of press cheeks capable of relative movement, one with respect to the other, from a position spaced apart from one another to enable a length of evenly spread 15 plug-forming material to be placed between them to a position approached to one another, said press cheeks having concave working surfaces so as to form together a hollow chamber when the press cheeks are 20 approached to one another for shaping the plug-forming material into a plug, a feeding device for feeding lengths of plug-forming material between said cheeks in the spaced apart position of the latter and 25 means for removing the formed plugs from the said hollow chamber.
6. In a machine for manufacturing mouth-piece plugs for cigarettes and cigarette tubes, the combination as set forth in claim 30 4 with driving means for the conveyor wheel, comprising a rotary driving member arranged so as to be displaceable with respect to the shaft, a drive-receiving member fixed on the shaft, a flexible drive transmission member passed round said driving and drive-receiving members and a spring connected to said driving member so as to urge the latter away from the shaft for uniformly tensioning the flexible drive transmission 35 member.
7. In a machine for manufacturing mouth-piece plugs for cigarettes and cigarette tubes, a pressing device having a pair of press cheeks capable of relative movement, one with respect to the other, from a position spaced apart from one another to enable a length of evenly spread plug-forming material to be placed between them to a position approached to one another, said press cheeks having concave working 40 surfaces so as to form together a hollow chamber when the press cheeks are approached to one another for shaping the plug-forming material into a plug, a feeding device 45 for feeding lengths of plug-forming material between said cheeks in the spaced apart position of the latter, means for removing the formed plugs from the said hollow chamber, spoon-ended members 50 arranged to receive said plugs in the interiors thereof and adapted to receive cigarette tubes on the exteriors thereof, the transverse axis of said hollow chamber measured in the direction of relative movement of the 55 one press cheek with respect to the other

being smaller than the corresponding axis of the spoon-ended members.

8. In a machine for manufacturing mouth-piece plugs for cigarettes and cigarette tubes, a pressing device having a pair of press cheeks capable of relative movement, one with respect to the other, from a position spaced apart from one another to enable a length of evenly spread plug-forming material to be placed between them to a position approached to one another, said press cheeks having concave working surfaces so as to form together a hollow chamber when the press cheeks are approached to one another for shaping the plug-forming material into a plug, a feeding device for feeding lengths of plug-forming material between said cheeks in the spaced apart position of the latter, means for removing the formed plugs from the said hollow chamber, spoon-ended members arranged to receive said plugs in the interiors thereof and adapted to receive cigarette tubes on the exteriors thereof, a rammer arranged to eject the plugs from the interior of the spoon-ended members and a stripper fixed to said rammer and arranged to slide upon the outer surface of the spoon-ended members for stripping the tubes therefrom. 80

9. In a machine for manufacturing mouth-piece plugs for cigarettes and cigarette tubes, a pressing device having a pair of press cheeks capable of relative movement, one with respect to the other, from a position spaced apart from one another to enable a length of evenly spread plug-forming material to be placed between them to a position approached to one another, said press cheeks having concave working 90 surfaces so as to form together a hollow chamber when the press cheeks are approached to one another for shaping the plug-forming material into a plug, a feeding device for feeding lengths of plug-forming material between said cheeks in the spaced apart position of the latter, means for removing the formed plugs from the said hollow chamber, spoon-ended members arranged to receive said plugs in the interiors 95 thereof and adapted to receive cigarette tubes on the exteriors thereof, having continuous tubular walls, a rammer arranged to eject the plugs from the interior of the spoon-ended members and a stripper fixed to said rammer and arranged to slide upon the outer surface of the spoon-ended members for stripping the tubes therefrom. 100

In testimony whereof I have signed my name to this specification. 110

FRIEDRICH LERNER. 115
